FIG. 4.

UNITED STATES PATENT OFFICE.

HARRY DIPPEL, OF PHILADELPHIA, PENNSYLVANIA.

CONCRETE-INSERT.

1,218,378.

Specification of Letters Patent.

Patented Mar. 6, 1917.

Application filed February 9, 1916. Serial No. 77,118.

To all whom it may concern:

Be it known that I, HARRY DIPPEL, a citizen of the United States, and resident of Philadelphia, county of Philadelphia, and 5 State of Pennsylvania, have invented an Improvement in Concrete-Inserts, of which the following is a specification.

My invention has for its object the provision of a suitable construction of metal insert for concrete ceilings which shall embody certain improvements over devices of a similar nature heretofore in use, in that it more snugly fits to the mold form or boards and hence, during the forming of the concrete ceiling, prevents the concrete working under the same; and in the finished ceiling, has its lower surface in smooth alinement with the concrete surface.

With the above and other objects in view, 20 the nature of which will be more fully understood from the description herein-after, the invention consists in the novel construction of concrete insert as herein-after more fully described and defined in 25 the claim.

In the drawings:—Figure 1 is a side elevation of one of my improved inserts before use; Fig. 2 is a plan view of the same; Fig. 3 is a sectional elevation showing the 30 insert attached to the mold form or board; and Fig. 4 is a sectional elevation of a modification of my invention.

2 is a vertical body having a screw-threaded hole 3 open at the bottom. The body is 35 preferably of considerable height compared with its diameter and has its upper end formed integral at 5 with a plurality of arms 4 having feet 6 at their lower ends. As shown, the arms are ribbed and hence 40 rigid, while their connections with the body are by the ductile portions 5 of relatively thin metal and hence yielding. These arms extend radially outward and downward and terminate in a plane which is not coincident 45 with the plane of the bottom of the body 2, as will be seen by reference to Fig. 1; and this is an important feature of my invention. The insert as a whole is made of cast iron 50 and then malleableized so that the parts 5 are ductile and flexible so that the arms 4" may be bent relatively to the body, for reasons to be later described. This ductile condition of the insert may be confined to the connecting portions 5 if so desired, as 55 these are the only parts to be subjected to bending; and the malleability or ductility

of these parts whereby they may be flexible without danger of breaking is another important feature of my invention.

In employing my invention in practice, the body 2 has its flat end resting upon the mold form or board 7 and with the feet 6 of the arms 4 normally hanging down with a space 8 between them and said board; the feet are then nailed down tightly with nails 9 and 65 in so securing them the arms 4 are bent downwardly about the ductile portions 5 until the feet 6 rest upon the form 7. In so securing the insert in position upon the form, the end of the body 2 is pressed or 70 drawn down upon the wooden surface with considerable force so as to practically indent the wooden surface to make a tight joint. The arms 4 insure the body being held vertically upward upon the mold or form, as 75 shown.

When the concrete is now thrown into the mold, it surrounds the insert and causes it to be embedded with the exception of the feet and body end; and when the concrete has 80 set, the insert will be strongly held in place and all hidden from view except the portion or portions which had tightly pressed upon the form or mold board. It will be understood that in springing down the arms 85 4 their feet 6 need not be made to touch the board or form, as the bending at 5 under this condition will be sufficient to insure the tight fit of the body 2 to the form surface desired. In this case the finished ceiling will not expose the feet at all, but only 90 the lower surface of the body, to which the fixture is to be attached. I have shown at 10 a reinforce steel rod which may be embedded in the concrete and pass between 95 the arm 4 and body 2 and hence act as an additional metal support for the insert, should the concrete crack or crumble under heat or other cause.

In the modification shown in Fig. 4, I 100 have all of the insert formed of ductile metal, the body 2 being composed of a piece of gas piping internally threaded at 3, and having a reduced neck 12 at the top and fitted with a stamped sheet metal spider providing the arms 4" corresponding to the arms 4 of the other figures. These arms 4" are bent at their top portions 5 adjacent the ring center part, so that they may bend 105 when applying the insert to the form. This 110 spider portion, providing the arms 4", is riveted in place by beating down the flanged

portion 13. In this way the entire insert 5 may be made of ductile metal and thereby overcome the necessity of employing malleable metal. The same general construction and mode of use are carried out in the modification of Fig. 4 as in the structure of the other figures.

It will now be apparent that I have devised a novel and useful construction which 10 embodies the features of advantage enumerated as desirable, and while I have in the present instance shown and described the preferred embodiment thereof which has been found in practice to give satisfactory 15 and reliable results, it is to be understood that I do not restrict myself to the details, as the same are susceptible of modification in various particulars without departing from the spirit or scope of the invention.

20 Having now described my invention, what I claim as new and desire to secure by Letters Patent, is:—

As an article of manufacture, an insert for concrete ceilings, etc., which consists of

a central elongated body provided with three 25 or more radiating arms extending from one end of said body and projecting obliquely outward away from the body and having their ends normally terminating in a plane slightly back of the plane of the other end 30 of the body, said arms each terminating in a foot and said feet widely separated and arranged at a considerable distance from the body and movable relatively thereto, and in which further the union of the arms with 35 the body is formed by flexible portions capable of bending without breaking, whereby the feet may be independently adjusted and sprung down when applying the insert to the false work and cause the body to press 40 tightly upon such false work.

In testimony of which invention I hereunto set my hand.

HARRY DIPPEL.
